UNITED STATES PATENT OFFICE.

HENRY A. MATTHEWS, OF WATERBURY, CONNECTICUT.

KNOB.

SPECIFICATION forming part of Letters Patent No. 449,908, dated April 7, 1891.

Application filed September 15, 1890. Serial No. 365,000. (No model.)

To all whom it may concern:

Be it known that I, HENRY A. MATTHEWS, of Waterbury, in the county of New Haven and State of Connecticut, have invented new 5 Improvements in Knobs; and I do hereby declare the following, when taken in connection with accompanying drawings and the letters of reference marked thereon, to be a full, clear, and exact description of the same, 10 and which said drawings constitute part of this specification, and represent, in—

Figure 1, a side view of the knob complete; Fig. 2, a longitudinal central section of the same; Fig. 3, a transverse section on line $x x$ of Fig. 2; Fig. 4, a modification in the attachment of the disk.

This invention relates to an improvement 20 in the construction of knobs such as made from a sheet-metal body and adapted for use upon stoves and for like purposes, the object 25 of the invention being a simple construction whereby a firm attachment of the knob may be produced; and the invention consists in the construction as hereinafter described, and 30 particularly recited in the claim.

The knob is made from sheet metal and consists of two parts, the body A and the head B, these two parts being struck to shape in suitable dies and the one closed upon the other 35 at their meeting edges, as at C. Before closing the parts together a metal disk D is introduced and the parts closed upon the disk so as to hold it firmly in place. To the disk a spindle E is attached by one end, the other 40 end projecting through the open end of the body. At the open end of the body a cup-shaped neck F is introduced, the open end inward, and the edge of the open end expanded within the body so as to be retained in position 45 in the body. The neck F is of cylindrical shape, corresponding to the opening through the body and so that the neck may slide back and forth or longitudinally in the body, as indicated in broken lines, Fig. 2. The closed 50 end of the neck is pierced for the passage of the spindle E, the neck being of larger internal diameter than the spindle. The neck is introduced before the parts A B are closed together. Around the spindle a spring G is ar-

ranged, one end bearing against the outer end of the neck and the other against the stationary disk D, so that the tendency of the spring is

to force the neck outward and into the position seen in Fig. 2, so that the inner end of the neck may come to a stop against the inner 55 side of the knob and prevent the entire forcing of the neck from the body. The spindle is constructed at its projecting end so as to be attached to the stove-door or whatever it may be. This may be in the form of a screw 60 or any other of the known attachments, the illustration showing a hole H transversely through the spindle, into which a pin may be placed after the spindle has passed through the door, or whatever it may be to which the 65 knob is to be attached.

In the construction of the knob the arrangement of the neck and spring is such that the outer end of the neck will come against the surface to which the knob is to be attached 70 and so that the neck will be forced inward, compressing the spring to some extent before the spindle is brought to its position in such attachment and so that the force of the spring will tend to clamp the thing to which the knob 75 is attached between the inner end of the neck and the fastening device of the spindle upon the reverse side, and thus hold the knob firm and steady in its place without the necessity of a close fit of the spindle in the hole through 80 which it passes.

In some cases it is desirable to prevent the rotation of the spindle, as when the spindle is screw-threaded and a nut applied upon the inside. To do this the disk D is interlocked 85 with the body. This may be done in various ways, the single illustration seen in Fig. 4 being sufficient. In this illustration the disk is represented as constructed with notches I, and tongues J are turned therein from the 90 body. This interlocking will hold the disk against rotation independent of the knob itself, and the spindle being firmly attached to the disk will be accordingly prevented from rotation. If desirable, the disk may be made 95 an integral part of the spindle. Under this construction not only is the knob held firmly in place when attached, but all the parts composing the knob are substantially inseparable, a desirable feature in this class of knobs. 100

While I prefer to make the part D in the form of a complete disk, it is not necessarily made a complete disk, and portions may be omitted, as indicated in broken lines, Fig. 4;

but in either case it is substantially a disk held firmly within the body.

I claim—

The herein-described knob, consisting of 5 the body A, having an open inner end, the head B, the body and head closed together, combined with a disk D, secured within the knob, a cup-shaped neck F within the open end of the body and so as to move longitudinally 10 therein, and the spindle E, attached to said

disk and extending through the outer end of the said neck with the spring G between the said neck and disk, substantially as described.

In testimony whereof I have signed this specification in the presence of two subscribing witnesses.

HENRY A. MATTHEWS.
